(57) **CLAIM**

The design for a garment with combined hood and neck gaiter, as shown and described.

DESCRIPTION

FIG. 1 is a perspective view of a garment with combined hood and neck gaiter showing the new design with the hood and neck gaiter in an up position.

FIG. 2 is a front view thereof.

FIG. 3 is a rear view thereof.

FIG. 4 is a right side view thereof.

FIG. 5 is a left side view thereof.

FIG. 6 is a top view thereof.

FIG. 7 is a bottom view thereof.

FIG. 8 is a perspective view thereof with the hood in a down position and the neck gaiter in an up position.

FIG. 9 is a front view thereof.

FIG. 10 is a rear view thereof.

FIG. 11 is a right side view thereof.

FIG. 12 is a left side view thereof.

FIG. 13 is a top view thereof.

FIG. 14 is a bottom view thereof.

FIG. 15 is a perspective view thereof with the hood and neck gaiter in a down position.

FIG. 16 is a front view thereof.

FIG. 17 is a rear view thereof.

FIG. 18 is a right side view thereof.

FIG. 19 is a left side view thereof.

FIG. 20 is a top view thereof; and,

FIG. 21 is a bottom view thereof.

The zig-zag lines and the broken lines that run within the zig-zag lines represent stitching that forms a part of the claim. The remaining broken lines, including the evenly spaced and the dot-dash broken lines, depict environment that forms no part of the claimed design.

1 Claim, 13 Drawing Sheets
